UNITED STATES PATENT OFFICE.

FRED C. NICHOLSON, OF CHATTANOOGA, TENNESSEE, ASSIGNOR TO SCOTT AND WILLIAMS, INCORPORATED, OF BOSTON, MASSACHUSETTS, A CORPORATION OF MASSACHUSETTS.

YARN-FEEDING MEANS FOR KNITTING-MACHINES.

1,346,049.

Specification of Letters Patent.

Patented July 6, 1920.

Application filed January 6, 1919. Serial No. 269,852.

To all whom it may concern:

Be it known that I, FRED C. NICHOLSON, a citizen of the United States of America, residing in the city of Chattanooga, in the 5 county of Hamilton and State of Tennessee, and whose post-office address is care of Scott and Williams, Incorporated, 366 Broadway, New York city, New York, have invented certain new and useful Improvements in 10 Yarn-Feeding Means for Knitting-Machines, of which the following is a specification.

My invention relates to knitting machines in which pivoted yarn feeding fingers 15 operate with the needles to supply yarn to the latter, and the object of my invention is to provide means whereby the yarn shall be taken by the desired needles with greater certainty. This is especially useful at the 20 beginning of a knitting operation, as for example, at the beginning of knitting the body of a stocking on to a transferred rib top. This object I accomplish by so constructing and operating the yarn-feeding 25 finger as that it can be adjusted toward and away from the line of needles. In a beginning knitting operation, I provide means automatically to move it up to the line of needles at the appropriate time, and move 30 it away again out of action, when desired, without danger of the finger colliding with the tops of any needles, when the finger is swung on its pivot.

In the accompanying drawings—

35 Figure 1 is a vertical sectional view of sufficient of a circular knitting machine to illustrate my invention as applied to a rib-top transfer machine;

40 Figs. 2 and 3 are diagrams, showing a yarn-feeding finger in different positions;

Fig. 4 is a perspective view.

In the drawing I have illustrated my invention as applied to a circular knitting machine of the general type disclosed in the 45 Scott Patents 1,150,547 and 1,150,549, dated August 17, 1915.

In the construction illustrated, there is a rotary needle cylinder 260 with needles *n* controlled by any suitable stitch cams which 50 are mounted on the segment 370. Over the top of the needles is a latch ring 550 pivoted on a cross pin 552 on a fixed standard 401 of the frame of the machine.

The yarn feeding fingers *F* are pivoted on

a pin 554 mounted in the arched portion 555 of the latch ring. The forward ends of these fingers which are provided with guide holes for the yarn adjacent to the needles are drawn down (when permitted by their thrust bars) to the active or feeding position by spiral springs *f*, each of which may be connected at one end to a hook on a pivoted finger *F* and at the other end to the cross pin 552. To lift each yarn finger *F* upwardly on its pivot from its active feeding position, a thrust bar 460 is employed, this thrust bar being operated at the appropriate time by a cam on a rotary drum 120, in the known way.

When a rib top is transferred to a knitting machine to begin the plain knitting of the leg of a stocking, for example, it is especially important, (as indeed it is at other knitting operations), to make sure that the 70 yarn from the yarn finger *F* shall be fed to 75 and taken by the desired needles without failure, and without danger of pressing off the stitches on the needles. In the Scott Patent 1,150,549, above mentioned, means are provided for automatically pushing certain needles outwardly toward the appropriate yarn-feeding finger *F* for that purpose.

According to the present invention, I 85 provide in a simple way for bringing the outer end of a yarn-feeding finger as close to the line of needles as may be desired, and thereby I am enabled to insure the feed of the yarn to the desired needles, even at a beginning knitting operation, such as knitting the body of a stocking onto a transferred rib top. For this purpose I so construct the pivotal mounting of the desired 90 yarn-finger *F* that as the yarn feeding end descends to its lowest position or when it 95 has reached that position, its forward end may be moved over toward the line of needles, that is to say, in a direction substantially at right angles to the length of the needles.

For this purpose I may make the pivotal opening in the yarn-finger for the passage 100 of the pivot pin 554 in the form of a slot *s*. And I provide means for moving the finger over in a horizontal direction toward 105 the line of needles at or toward the end of the descending movement of the yarn feeding end of the finger. This may be accom-

plished automatically by the action of a suitable thrust bar 460°, other than the ones which lift the yarn fingers. A lever 701, pivoted at 610 to a bracket on the latch ring 550, extends backwardly past the arch 555, and is there provided with a cam-like projection 700 in a position to act upon the rear end of the yarn finger F. This lever 701 is provided between its pivot and its 10 acting end with a laterally projecting pin 707 in position to be acted on by the upper end of a thrust bar 460° in a manner similar to that described for the like bar in the above mentioned Scott Patent No. 1,150,549 15 for the lever. This pin 707 is made adjustable by being mounted eccentrically on a cylindrical plug 705, rotarily adjustable in a bore in the lever 701 and secured in adjusted position by a set screw 706. The 20 operation of the parts is so timed that when the thrust bar 460°, which has the duty to raise this yarn finger F on its pivot, descends and allows the yarn-carrying end of the finger to descend under the action of 25 gravity and its spring f, as indicated in Fig. 2, the bar 460° will rise and lift the lever 701 so as to cause the projection 700 on the rear end of this lever to press the yarn finger forward in a horizontal direction toward the needles, as indicated in Fig. 3, and bring it as close as may be necessary 30 to insure the yarn engaging the appropriate needles. When the thrust bar 460° descends again, and allows the rear end of 35 the lever 701 to drop, the spring f will draw the yarn guide F away from the line of needles, so that when thereafter, this yarn finger is raised again on its pivot by

the rise of its thrust bar 460°, the yarn finger will not collide with the needles which may have been less elevated for any purpose in the knitting operation.

While my described invention is thus particularly useful for securing the proper feeding of the yarn to certain needles at a "set up" or beginning knitting operation, as explained, it is useful for other knitting operations.

I claim as my invention:

1. A knitting machine having needles and operating means therefor in combination with a yarn finger having a slotted pivotal mounting, adjustable means to move the finger over toward the line of needles on the descent of the finger, and a spring to withdraw the finger, as it is raised.

2. A knitting machine having needles and operating means therefor in combination with a pivoted yarn finger and means acting on the rear of said finger to move it over toward the line of needles on the descent of the finger to the feeding position, and means to move it away from the line of needles again, when the finger is raised.

3. A knitting machine having needles and operating means therefor in combination with a pivoted yarn finger and means acting on the rear of said finger to move it over toward the line of needles on the descent of the finger to the feeding position and a spring to withdraw the finger from the needle line.

In testimony whereof I have signed my name to this specification.

FRED C. NICHOLSON.
